US0D1085302S

(12) **United States Design Patent** (10) Patent No.: **US D1,085,302 S**
(45) Date of Patent: ** Jul. 22, 2025

(54) **FLOAT**

(71) Applicant: **GUANGZHOU GUARDVALUE TECHNOLOGY LTD.**, Guangzhou (CN)

(72) Inventor: **Weihua Zhong**, Guangzhou (CN)

(73) Assignee: **GUANGZHOU GUARDVALUE TECHNOLOGY LTD.**, Guangzhou (CN)

(**) Term: **15 Years**

(21) Appl. No.: **29/823,607**

(22) Filed: **Jan. 19, 2022**

(51) LOC (15) Cl. 21-03

(52) U.S. Cl.

USPC **D21/803**; D6/596

(58) Field of Classification Search

USPC D21/803, 804, 807-810; D6/596, 601, D6/604

CPC A47C 15/006; A47C 15/008

See application file for complete search history.

(57) **CLAIM**

The ornamental design for a float, as shown and described.

DESCRIPTION

FIG. 1 is a perspective view of a float, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken line showing of the float is for the purpose of illustrating article and forms no part of the claimed design.
